UNITED STATES PATENT OFFICE

MILTON ROY SHEEN, OF PHILADELPHIA, PENNSYLVANIA, ASSIGNOR TO TUNNEL MACHINE MANUFACTURING AND ENGINEERING COMPANY, OF PHILADELPHIA, PENNSYLVANIA, A CORPORATION OF DELAWARE

TUNNELING MACHINE

Application filed June 16, 1928. Serial No. 285,797.

My invention relates to the method and apparatus for advancing a tunneling machine. My invention is particularly adapted for use in connection with tunneling machines which are forced through an excavation made in the earth of about the same diameter as the machine casing, in which practice the loose earth and especially the moist earth adheres to the casing, thus resisting the advancement of the latter.

The object of my invention is to provide a method by which the casing may be loosened from the surrounding earth, consisting of imparting a vibratory motion to the casing which will loosen the casing and allow it to be readily advanced; a further object of my invention is to provide a vibrator suitable for setting up vibrations in the tunneling machine casing; a still further object is to provide means for varying the frequency of the vibrations; and a still further object is to provide two or more vibrators for increasing the amplitude of the vibrations and also for varying the speed of the vibrators relatively to each other.

Referring to the accompanying drawings, Fig. 1 is a vertical longitudinal sectional view of a tunneling machine, embodying my invention; Fig. 2 is a view similar to Fig. 1, drawn on a smaller scale, illustrating more fully my novel method of advancing the machine; Fig. 3 is a transverse section on line 3—3, Fig. 1; and Fig. 4 is a longitudinal sectional view of the vibrator as on line 4—4, Fig. 3, drawn on a larger scale.

In the accompanying drawings, in which like reference characters refer to like parts, 10 represents the cylindrical casing of a tunneling machine now in general use, comprising a rotary cutter 12 located at the forward end of the casing. Said cutter 12 is mounted in a bearing 13 and rotated by motor 14. Within the casing 10 is a cam 16, shown in Fig. 2, which is rotated by a motor 17 relatively to the casing and adapted for pressing against the tunnel structure 18, formed by blocks 19 which are inserted successively as the cam is rotated to form the structure at the rear end of the casing 10. As the structure 18 is formed,

the rotation of the cam 16 forces the casing forward as the cutter 12 forms an opening in the earth for the advancement of the machine.

Tunneling machines of this, or similar, character are advanced with great difficulty when the surrounding earth adheres to the outer surface of the casing, and I have devised the present method and apparatus for relieving the casing from the resistance due to the surrounding earth and also for freeing the rear end of the casing 10 from the structure 18, due to the pressure exerted by the cam 16 against the blocks 19, which pressure tends to expand the structure 18 and slightly increase the diameter of the same.

My novel method of freeing the casing 10 from the resistance exerted by the earth surrounding the casing and the internal friction due to the expansion of the structure 18 at the rear end of the casing 10, consists of setting up a vibratory motion in the casing, by which method the casing may be readily advanced under any conditions, such as moist earth or clay, which conditions heretofore offered so much resistance to the outer surface of the casing that it was difficult to apply sufficient power back of the casing to advance it through the excavation made by the cutter 12.

A preferred form of apparatus is illustrated in the drawings for carrying out my novel method of vibrating the casing of the tunneling machine, comprising a vibrator 20, consisting of a shaft 21, rotatably mounted in bearings 22 and 23, which are rigidly secured to the inner surface of the casing 10. Upon the shaft 21 is secured an enlarged drum 25, located between the bearings 22 and 23. Upon the drum 25 are weights 27 and 28 adapted for throwing the drum out of balance. Said weights are detachably secured to the drum by the bolts 29 and may be readily replaced with weights of different sizes. When the shaft 21 is rotated said weights will set up vibrations which will be imparted through the bearings 22 and 23 to the casing 10, causing the entire casing to vibrate.

The shaft 21 of the vibrator is rotated by

a variable speed electric motor 30 of standard type. A sprocket wheel 31 is secured to the shaft 21 of the vibrator and is rotated by a sprocket chain 32, driven by a sprocket wheel 33, secured to the shaft 34 of the motor 30.

A controller 35 is provided for varying the speed of rotation of the motor, whereby the pulsations of the vibrator may be regulated to suit the conditions under which the casing 10 may be operated.

In large tunneling machines it is necessary to use two or more vibrators, due to the fact that a single vibrator cannot be increased in size and weight beyond certain limitations. Fig. 3 shows a second vibrator 40 of similar construction to the vibrator 20. Said vibrator 40 is rotated by a sprocket chain 41 from a sprocket wheel 42 secured upon the shaft 34 of the same motor 30 which drives the vibrator 20.

The vibrators 20 and 40 may be driven at the same speed of rotation so that the pulsations of the vibrators will be in unison, or by changing one of the sprocket wheels 33 or 42 for a wheel of a different diameter the vibrators may be rotated at different speeds, causing an irregular pulsation in the two vibrators, which at certain periods will be in unison and at intermediate periods will oppose each other, the effect being a powerful vibration when the vibrators are acting in unison.

Various changes may be made in the operation and construction from the above disclosure without departing from my invention.

I claim:

1. A tunneling machine comprising a casing, a bearing secured upon the casing, an unbalanced member rotatably mounted in said bearing, and means for rotating said member to impart vibrations to the casing.

2. A tunneling machine comprising a casing, a bearing secured upon the casing, a shaft rotatably mounted in the bearing, a weight eccentrically positioned upon said shaft, and means for rotating the shaft.

3. A tunneling machine comprising a casing, a bearing secured upon the casing, a shaft rotatably mounted in the bearing, a drum secured upon said shaft, a weight detachably secured upon said drum forming an unbalanced member, and means for rotating said shaft.

4. A tunneling machine comprising a casing, a plurality of vibrators secured within the casing, and means for operating said vibrators to impart to the casing vibrations in unison at certain periods of rotation having greater amplitude than could be obtained by a single vibrator.

5. A tunneling machine comprising a casing, a plurality of unbalanced members rotatably mounted upon the casing, said mem-

bers located at different positions within the casing, and a motor operatively associated with said members for rotating the same and imparting a vibratory motion to the casing.

6. A tunneling machine comprising a casing, a plurality of unbalanced rotatable members mounted upon the casing, a motor and gearing operatively associated with said members and said motor for rotating said members and imparting vibrations to the casing.

In testimony whereof I affix my signature.

MILTON ROY SHEEN.
